[57] ABSTRACT

In a circuit arrangement for the horizontal deflection in television display apparatus using two switches (thyristors), a coil is used to compensate for energy losses in which the energy consumption is controlled by means of a transductor in order to maintain the amplitude of the deflection constant. The functions of the coil and of the control transductor are formed by one transductor whose leg on which the coil is wound has an airgap.

CIRCUIT ARRANGEMENT FOR GENERATING A SAWTOOTH CURRENT FOR THE HORIZONTAL DEFLECTION IN TELEVISION DISPLAY APPARATUS

The invention relates to a circuit arrangement for generating a sawtooth current for the horizontal deflection in television display apparatus in which a first switch is operative during the line scan period and a second switch is operative during the line flyback period, a current being applied through a coil for implementing losses, while the power winding of a transductor is arranged in parallel with said coil for controlling the energy consumption.

Such a circuit arrangement is known from U.S. Pat. No. 3,517,253. In this arrangement the said coil and the control transductor are separate elements. As a result a fairly large quantity of material is required and furthermore additional stray fields are to be taken into the bargain which cause losses and disturb the function of other parts in the deflection circuit.

These drawbacks of the known circuit arrangement may be obviated in a simple manner according to the invention and to this end the circuit arrangement according to the invention is characterized in that the coil and the power winding of the transductor are each wound on an outer leg, and the control winding of the transductor is wound on the central leg of a three-legged core of magnetic material.

In order that the invention may be readily carried into effect, an embodiment thereof will now be described in detail by way of example, with reference to the accompanying diagrammatic drawing in which

FIG. 1 shows the principle circuit diagram of the arrangement according to the invention and

FIG. 2 shows an embodiment of the element formed by the coil and the transductor.

In FIG. 1 a primary winding L_1 , a secondary winding L_2 to which the deflection coil L_3 is connected, an EHT winding L_4 and a further secondary winding L_5 are provided on the line deflection transformer T_1 of a television display apparatus not further shown. The low end of primary winding L_1 is connected to the S-capacitor C_1 the other terminal of which is connected to earth. The high end of primary winding L_1 is connected to the anode of a first thyristor T_1 and to the cathode of a first diode D_1 , while the cathode of thyristor T_1 and the anode of diode D_1 are connected to earth. Elements T_1 and D_1 constitute a switch S_1 which is conducting during the line scan period. Furthermore the high end of primary winding L_1 is connected through capacitor C_2 and C_3 and through an inductor L_6 to a connection point 11 of a magnetic element 1 to be described hereinafter. The anode of a second thyristor T_2 and the cathode of a second diode D_2 are likewise connected to connection point 11 while the cathode of thyristor T_2 and the anode of diode D_2 are connected to earth. Elements T_2 and D_2 constitute a switch S_2 which is conducting during the line flyback period. The junction of capacitors C_2 and C_3 is connected to earth through a further capacitor C_4 .

The power windings L_7 and L_8 of magnetic element 1 are jointly connected at one end through a connection 12 to the positive terminal of a voltage source U_B , while the other end of the power winding L_8 is connected through a diode D_4 shown in broken lines and the other end of power winding L_7 is connected

through a diode D_3 to connection point 11, the conductivity direction of the diodes being shown in FIG. 1. A connection 13 of the control winding L_9 is connected at one end to the junction of primary winding L_1 and

- 5 C_1 and at the other end to a connection of a resistor R_1 the other connection of which is coupled to the other connection 14 of control winding L_9 . Control winding L_9 receives a control current in known manner through the control amplifier 2 not further described, which 10 current is dependent on the voltage induced in winding L_5 ; this control current is therefore dependent on possible variations of the alternating voltage across winding L_1 . Resistor R_1 damps parasitic oscillations, if any. Thyristor T_1 is controlled by a control voltage which is derived 15 from power winding L_8 through a tap 15 and is applied to the gate of thyristor T_1 through a capacitor C_5 , a resistor R_2 and an inductor L_{10} . The gate of thyristor T_2 is connected to the line oscillator.

During the line scan period switch S_1 conducts and the deflection current oscillates in known manner in the circuit constituted by elements L_1 and C_1 . However, during the line flyback period switch S_2 conducts and switch S_1 is cut off. During this period elements L_1 and C_1 are arranged in series with elements C_2 , C_3 and L_6 . A half oscillation occurs in this circuit during the flyback period. Simultaneously a current flows from voltage source U_B through winding L_8 and through switch S_2 to earth. The energy then stored in winding L_8 is used for charging capacitor C_2 and C_3 during the scan period when switch S_1 conducts and switch S_2 is cut off so that the losses in the deflection circuit are implemented.

The amplitude of the deflection current depends on the voltages which are present at the end of the scan period across capacitors C_2 , C_3 and C_4 . By varying the inductance of the parallel arrangement of windings L_7 and L_8 these voltages and consequently the amplitude of the deflection current can be controlled. In the 40 known circuit arrangement this variation is achieved in that the power winding of a transductor is arranged in parallel with winding L_8 which is present as an independent element, while a control current flows through the control winding of the transductor.

45 According to the invention the function of winding L_8 and of said transductor can be combined advantageously in one element as is shown in FIG. 1 and as will be described in greater detail with reference to FIG. 2. For components shown in FIG. 1 the same reference numerals have been used in FIG. 2.

Windings L_7 and L_8 are provided on the outer legs 31 and 33 of a core 3 of magnetic material while the central leg 32 supports control winding L_9 . An airgap is provided on leg 33. When the control current in control winding L_9 is directed from connection 13 to connection 14, windings L_7 , L_8 and L_9 must have the winding sense shown in FIG. 2. As a result the induction flux in the legs 31 and 33 generated by the currents in windings L_7 and L_8 is increased by the flux generated by the control current in leg 32. This is shown in greater detail by means of broken lines in FIG. 2.

65 During the line flyback period switch S_2 conducts and a current flows from connection 12 through winding L_8 which generates a magnetic field in leg 33. Energy is stored in this winding. Current cannot flow during the flyback period in winding L_7 because diode D_3 is then blocked.

During the line scan period switch S_1 conducts and switch S_2 is blocked. The resonant network consisting of elements L_8 , L_6 , C_2 , C_3 and C_4 is then connected between supply voltage U_B and ground. Since the energy is stored in winding L_8 , capacitor C_2 , C_3 and C_4 are being charged. When the voltage of these capacitors has become so high that the voltage at connection 11 exceeds the voltage at connection 12, diode D_3 becomes conducting and a current originating from winding L_8 flows through winding L_7 . By varying the control current it is possible to vary the inductance of winding L_7 so that also the inductance of the parallel arrangement of windings L_8 and L_7 varies. This results in a variation of the voltage at the capacitors C_2 , C_3 and C_4 at the end of the line scan period and consequently in a variation of the amplitude of the deflection current.

It is achieved by the airgap in leg 33 that the control current flowing through winding L_9 does not noticeably influence the inductance of winding L_8 during the flyback period and as long as diode D_3 does not conduct. When a current flows through winding L_7 the inductance of the parallel arrangement of windings L_7 and L_8 is a function of that of winding L_7 and therefore varies as a function of the control current.

It is apparent from the foregoing that the direct current taken up by the arrangement, which current flows through diode D_4 which is arranged in series with winding L_8 , continues to flow in the same direction so that the diode is maintained conducting. Diode D_4 may therefore be omitted.

The magnetic core 3 having an airgap in outer leg 33 may be manufactured in an advantageous manner by inserting an intermediate layer consisting of magnetic material into legs 31 and 32 when two E-shaped core parts are combined. If only one part of the cross-section of leg 31 is filled with magnetic material the intermediate layer is saturated when the magnetising current initially increases and the other part of the core is saturated when the magnetising current further increases. As a result a continuous transition from the unsaturated state to saturation in leg 31 takes place (the knee in the B-H curve thereof is rounded off) so that

the inductance of winding L_7 can be controlled continuously. Alternatively the airgap may be obtained by shortening only one of the parts of leg 33 in an E-shaped core, which is cheaper than shortening both parts.

What is claimed is:

1. A circuit for energizing a deflection system from a power source in accordance with a control signal, said circuit comprising a transductor having a central and first and second outer legs; means for storing energy during flyback periods comprising a first coil wound about said first leg and a first switching means coupled to said first coil and conducting during said flyback periods for coupling said first coil to said power source during said flyback periods; means for energizing said deflection system during scan periods comprising a second switching means conducting during said scan periods and coupled to said first winding for coupling said first winding to said deflection system during said scan periods and for effecting energy transfer from said first winding to said deflection system; and means for controlling the amount of said energy transfer comprising a second power coil wound about said second leg and coupled to said first coil, and a control coil means wound about said center leg for receiving said control signal.

2. A circuit as claimed in claim 1 wherein said first leg has a gap.

3. A circuit as claimed in claim 2, wherein said transductor comprises two E-shaped cores and a pair of intermediate layers each comprising a magnetic material disposed between the two parts of the central and second outer legs respectively.

4. A circuit as claimed in claim 3, wherein the intermediate layer in the second outer leg fills only a part of the cross-section of said leg.

5. A circuit as claimed in claim 2, wherein said transductor comprises two E-shaped cores, each of said legs having two parts, at least one of the two parts of the first outer leg being shorter than the parts of the remaining legs, whereby said gap is formed.
